PUMP

Jean Louis Léon Alexandre Albert Moulet,
Boulogne - Sur - Seine, France, assignor to
Martin, Moulet & Cie., Oullins, France

Application July 18, 1930, Serial No. 468,883, and
in France March 5, 1930

3 Claims. (103—42)

The present invention relates to pumps which are particularly adapted for pumping petrol, or other liquids which dissolve or otherwise act upon lubricants, and it has for its object to provide a disposition whereby the delivery of the pump is automatically limited or interrupted whenever a certain resistance opposes the delivery, without the delivery pressure being however allowed to materially vary. This feature is particularly desirable in the case of direct fuel feeding of carburetors for internal combustion engines. In this particular application, the parts controlling the fuel inlet to the carburetor (such as the float and needle valve) oppose a certain resistance to the delivery: in order to insure efficient operation, it is necessary that the flow of the pump should be automatically regulated under the effect of this very resistance, so that the delivery pressure should remain constant and should not affect the operative conditions of said controlling parts (such as the float and needle valve).

The arrangement according to the invention, which may be applied in connection with all types of pump, resides in that one of the walls or one portion of the walls of the pump body is caused to move automatically when the pressure in such pump body reaches a predetermined value, so as to establish a direct communication between the suction and the delivery chambers of the pump, without the help of any conduit or piping, the by-pass flow thus provided being parallel with said movable wall or wall portion in order to prevent the latter from being affected by the momentum of the liquid in motion.

Due to this arrangement, the pumping operation is automatically reduced or stopped inside the very body of the pump where the volumetric variations take place. Moreover, friction inside the pump is mostly suppressed; when the pump is used for pumping petrol or any other lubricant dissolving liquid, the danger of seizing and rapid wear are thereby considerably reduced.

Another feature of the invention consists in using this particular arrangement for the purposes of priming the pump or causing the latter to run idle.

Further features of the invention will be disclosed in the following description, with reference to the accompanying drawings, which is only given by way of example, and in which:

Fig. 1 is a longitudinal section of a rotary volumetric pump, on line 1—1 of Fig. 4.

Figs. 2 and 3 are transverse sections on lines 2—2 and 3—3 of Fig. 1, respectively.

Fig. 4 is a plan view.

Figs. 5 and 6 are transverse sections on lines 5—5 and 6—6 of Fig. 1, respectively.

Fig. 7 shows a modified form of the arrangement shown on Fig. 1.

Fig. 8 shows diagrammatically an axial section of an embodiment of this invention, as applied to a reciprocating pump, and

Fig. 9 is a transverse section of Fig. 8.

In the drawings, 1 is the body of the pump, having two bosses inside which are provided a suction valve box 2 and a delivery valve box 3; the construction thereof will be hereinafter described.

Inside the body of the pump is secured a sleeve 23 comprising an eccentric cage 23^a of large diameter and a smaller portion forming a bearing 23^b. In eccentric cage 23^a is rotatably mounted a drum 24, integral with a shaft 24^a supported in bearing 23^b and whose end has a slit 23^c adapted for connection with any operating member fitted with a blade engaging slit 23^c whereby it is revolved.

Drum 24 has a transverse groove wherein are fitted two blades 25 and 26 (Fig. 5) each having one or a plurality of blind holes for housing spiral springs 27 and 28, which tend to keep the blades or vanes apart from one another and thereby constantly maintain the tips of the vanes in contact with the inner side of eccentric cage 23^a. Said vanes divide the crescent-shaped interval between cage 23^a and drum 24 into two cells 29^a and 29^b. When rotation takes place in the direction of arrow *f*, it will be seen that cell 29^a is connected through a duct 30 with the suction pipe and cell 29^b through a duct 31 with the delivery pipe.

Shaft 24^a extends through a stuffing-box made of a joint 32 clamped between two surfaces, one belonging to bearing 23^b and the other to a spacer 33. Said spacer is applied against the joint by a hollow nut 34 and a powerful spiral spring 35, housed in nut 34, and adapted to resiliently press spacer 33 against the joint, in order to avoid leakage in case of wear of the joint. Nut 34 has a longitudinal groove 34^a, engaged by the stem of a set-screw 36.

Spacer 33 also has a longitudinal groove 33^a, engaged by the stem of a set-screw 37, and a chamber 33^b, connected with a circular groove 105 33^c, leading through a duct 38 into a cavity wherein is screwed a pressure lubricator. Alternatively said cavity may be stopped by a plug 39, the lubricant being supplied under pressure through a duct 40 connected for instance with 110

a pressure lubricating pipe from the engine on which the pump is mounted.

To the body of pump 1 is attached, by means of bolts such as 41, a casing 42 containing an elastic piston or bellows 43 which forms an impervious envelope and has transverse folds so as to expand or retract longitudinally.

One end of the elastic piston has a fluidtight joint with a stationary disc 44, clamped between casing 42 and pump body 1, while its movable end is connected by a disc 45 to a sleeve 46 in which is secured a rod 47. Said rod has a ball-shaped tip held by a hard bearing member 48 in a cup 49 integral with a movable wall or spider 50. Said spider 50 comprises an annular part having an accurately machined and lapped or ground face which fits accurately the corresponding face, also thoroughly machined and ground or lapped, of drum 24 and of the cage.

Spider 50 is therefore capable of imperviously sealing the pump body and constitutes one of the walls or wall portions of said pump body.

Spider 50 (Fig. 3) is hollowed out at 50^b, thus leaving central webs 50^a which hold cup 49; the latter fits in a bore provided between two sector-shaped bosses 44^a, 44^b at the center of disc 44. Said bosses extend through the hollowed out portions 50^b of spider 50, and serve as an axial thrust member for drum 24 and also prevent spider 50 from being driven in rotation by the drum.

Spider 50 has a hole 50^c (Fig. 6) registering with a port 44^c in disc 44, whereby the inside of the pump body is in communication with the inside of the elastic piston or bellows.

Within sleeve 46 is arranged a spiral spring 51, bearing at one end against a nut 52, screwed upon a socket 53 adapted to rotate in casing 42 and at the opposite end against the bottom of sleeve 46, thus constantly tending to contract the elastic piston and to press spider 50 against the ground surfaces of drum 24 and of cage 23^a.

An adjusting knob 54, attached to socket 53, is adapted to rotate the latter. Said socket has a shoulder 53^a, by which it is prevented from moving axially, so that when knob 54 is rotated, ring 52 screwed on the socket is caused to move axially and is prevented from rotating by a screw 55, extending through a bore in casing 42. Said bore has a shoulder 55^a adapted to stop the inward motion of the head of screw 55, thereby limiting the inward movement of ring 52.

A rod 56, screwed into sleeve 46, is slidably mounted in socket 53 and has an integral operating knob 57, for imparting longitudinal displacement to said rod.

Casing 42 may be filled with a lubricant, supplied from a lubricator such as 58 and may be drained off through a plug such as 59, located at the bottom of the casing.

Fig. 2 shows the construction of the valves. The suction valve box has a chamber 2^a containing a valve 4 coacting with a valve seat 5. The lift of said valve is limited by a stop member 6 having a flange resting on a shoulder of chamber 2^a and held in position by a spiral spring 7, bearing on a cap 8 which closes the top part of the valve box, tight sealing thereof being secured by a joint 9.

The boss forming the suction-valve box is extended by a chamber 2^b containing a filter 10, held in position by a spiral spring 11 bearing on plug 12, which closes the lower portion of chamber 2^b, with the interposition of an impervious

joint 13. 14 denotes the suction pipe of the pump.

Boss 3 contains the discharge valve 16, associated with the same elements as the suction valve box. 22 denotes the delivery pipe of the pumps.

The operation of the pump is as follows: shaft 24^a being imparted a circular motion drives drum 24 inside eccentric cage 23^a. Displacement of vanes 25 and 26 produces volumetric variations in cells 29^a and 29^b. The liquid is sucked up through suction valve box 2 and delivered through delivery valve box 3.

Spider 50 being kept tight against the ground surface of the drum and the cage, both through the action of elastic piston 43 and of spiral spring 51, the inner capacity of the body of the pump is imperviously closed; the pump works in the manner of an ordinary rotary pump.

Through chamber 33^b and ducts 38 and 40, lubricant is supplied to shaft 24^a under a pressure which exceeds the pressure of delivery of the pump; lubrication is thus efficiently insured, the stuffing-box being constantly soaked with lubricant. Even when the liquid to be pumped is petrol, no seizing can take place in the stuffing-box.

As long as delivery of the pump remains unobstructed, spider 50 remains tightly pressed against the drum and the cage. However, when the delivery of the pump becomes greater than the demand, the delivery pressure increases, said pressure being transmitted to the inside of the elastic piston through holes 50^c and 44^c. When such pressure reaches a predetermined value, it overcomes the tension of elastic piston 43 and of spring 51, spider 50 recedes from its seat, and a by-pass flow of variable amount takes place, parallel with the movable wall or spider inside the very chamber where the volumetric variation is produced. As a consequence, wall 50 is not affected by the momentum of the liquid in motion, in contradistinction with what takes place with pumps comprising a by-pass piping and valves, the valves always opening in the direction of the liquid current in the by-pass piping.

The delivery of the pump is selected in excess of that required, so that spider 50 will almost constantly recede from its seat, thus considerably reducing friction inside the pump; the latter may thereby properly work with the only lubrication provided for shaft 24^a.

Moreover, the movement of the movable wall 50 limits the delivery pressure down to a predetermined value, which is independent of the speed of rotation. The pump is thus "self regulating" and may be used for feeding carburetors of internal combustion engines provided with a constant level fuel tank or with a fuel dosing device.

Suction and discharge valves are required to insure efficient working of the pump at low speeds of rotation, and in the case of a great height of suction.

In the case of low speeds, the delivery valve opposes any return of liquid from the delivery pipe to the pump and avoids any fall of pressure detrimental to efficient working.

Both the suction and delivery valves open in the same direction thus obviating failing of the pump during temporary stoppage.

Moreover, if rod 56 is imparted a reciprocating motion, a variation of volume is produced inside elastic piston 43, and transmitted through

holes 44^c and 50^c to the inside of the pump body, provided with both valves.

The elastic piston and the valves constitute an auxiliary pumping means, which may be actuated from the outside, without the drum being in motion, such means being particularly useful for priming the pump by hand.

Furthermore, through the medium of rod 56 and knob 57, spider 50 may be held away from the drum, thus producing, inside the pump body, a by-pass whose delivery is equal to or greater than the delivery of the pump, which latter may thus be limited or annulled, the pump then running idle.

15 The pump may be locked in such position by any suitable means, adapted to keep spider 50 away from its seat.

In some cases, especially when it is desired to preserve the power of an engine at a high altitude, the latter is associated with a compressor adapted to deliver air under varying pressure into the carburetor. In order to obtain efficient working of the carburetor, the delivery pressure of the fuel to the carburetor should vary simultaneously and by the same amount.

20 Such working condition is readily fulfilled without any extra mechanism, with the use of the hereinbefore described pumping system. For this purpose, that is in order to balance the pressures on the elastic piston, a pressure equaling that exerted on the carburetor by the compressor is transmitted to casing 42. By way of example, a special pipe may be provided on the casing, or lubricator 58 or plug 59 may be replaced by a 25 coupling for connecting casing 42 with the compressor discharge end.

Such working condition is readily fulfilled without any extra mechanism, with the use of the hereinbefore described pumping system. For this purpose, that is in order to balance the pressures on the elastic piston, a pressure equaling that exerted on the carburetor by the compressor is transmitted to casing 42. By way of example, a special pipe may be provided on the casing, or lubricator 58 or plug 59 may be replaced by a coupling for connecting casing 42 with the compressor discharge end.

It will be readily understood that the elastic piston or bellows may be eliminated, whereby spider 50 would be directly responsive to the delivery pressure, as shown on Fig. 7, which shows a rotary pump similar to that illustrated on Fig. 1, with this difference however that spider 50 is replaced by a solid disc connected with a deformable wall 90 adapted to separate the pump body from the chamber 91 of casing 92, subject to atmospheric pressure or to be delivery pressure of the feeding compressor. The operation is identical with that above described.

Broadly, the above described construction is given solely for the sake of example, and it may in many ways be altered without getting out of the scope of this invention. For instance, bellows 43 may be replaced by a membrane or a deformable partition, etc. . . . while remaining within the 55 scope of the invention.

Moreover, the invention is applicable to pumps of any other types, rotary or reciprocating, volumetric or centrifugal, gear pumps, pumps comprising a number of movable blocks, arranged within one another and having relative movements producing volumetric variations, etc. . . .

Thus, Figs. 8 and 9 illustrate an application of this invention to a reciprocating pump of a conventional type, in which 70 denotes the cylinder, 71 the piston, dividing the cylinder into two chambers 70^a and 70^b, 72 the suction valve, 73 the delivery valve and 74 the piston valve.

The wall portion 75 is slidably mounted in a guide 70^c provided in cylinder 70. Said wall portion is operatively connected with the free end of an elastic piston or bellows 76, through the medium of a sleeve 77. The other end of the elastic piston is attached to a ring 78, clamped between cylinder 70 and casing 79. A spiral spring 80, housed between the bottom of sleeve 77 and an

adjusting socket 81 screwing on a threaded stem 82, presses wall 75 against the piston. A rod 83, fitted with a knob, is adapted to move wall 75 from the outside. A hole 75^a connects top chamber 70^b with the inner portion of the piston.

80

The operation is identical with that above described in connection with the rotary pump. The pump being primed, when the piston moves from bottom to top in the direction of arrow f¹, liquid is sucked up through valve 72 and discharged through valve 73, and wall 75 bears against the piston as long as the delivery remains unobstructed.

85

However, when the pressure exceeds a predetermined value, the same being exerted inside the bellows tends to move wall 75 away from the piston thereby creating direct communication between chambers 70^a and 70^b.

90

It should be noted that with this system of pumps, the efficient stroke, causing suction and delivery, is the upward stroke, while the downward stroke only serves to transfer the liquid from chamber 70^a into chamber 70^b and to bring back the piston to its lowermost point ready for another efficient stroke.

95

It will be seen that, during the efficient stroke, piston 71 sucks up through one of its faces and delivers through the other, substantially after the manner of the vane in the rotary pump hereinbefore described. Also as in the preceding case, the action of the movable wall section provides direct communication between the suction and delivery sides in the very cavity where volumetric variation takes place, when the pressure reaches a predetermined rate, the liquid flowing in a direction parallel to the movable wall section.

100

It should also be noted that operation of rod 93 through outside means may cause priming of the pump, with the piston at rest; the pump may also be put out of operation by keeping the wall section 75 apart from the piston, through the medium of said rod.

105

Having now described my invention what I claim as new and desire to secure by Letters Patent is:

110

1. In a pump, the combination of a pump body having a movable wall section, pumping means working along said wall section, a deformable wall operatively connected with said wall section, means whereby the delivery pressure is exerted on one face of said deformable wall and on both sides of said movable wall section, and yielding means for counteracting said pressure.

115

2. In a pump, the combination of a pump body having a movable wall section, pumping means working along said wall section, bellows operatively connected with said wall section, means for connecting the inner side of said bellows with the delivery side of said pump, and resilient means adapted to press on the outer side of said bellows.

120

3. In a pump, the combination of a pump body having a resiliently movable wall section and pumping means working in said pump body along said wall section, a suction valve, a discharge valve, and means for actuating said movable wall section independently of said pumping means for priming said pump.
